UNITED STATES PATENT OFFICE.

JAY H. METCALF, OF GRAND RAPIDS, MICHIGAN.

BIER CONSTRUCTION.

Application filed November 24, 1923. Serial No. 676,806.

To all whom it may concern:

Be it known that I, JAY H. METCALF, a citizen of the United States of America, residing at Grand Rapids, in the county of

5 Kent and State of Michigan, have invented certain new and useful Improvements in Bier Construction; and I do hereby declare the following to be a full, clear, and exact description of the invention, such as will 10 enable others skilled in the art to which it appertains to make and use the same.

This invention relates to a bier which may be used as a support for caskets, which is quickly and readily disassembled so that 15 it may be made to occupy very small space when it is desired to transport the same, and which may be put up as a more or less permanent fixture in a show room on which a casket or coffin may be placed for display.

20 In addition, this construction may be used as a screen to cover a truck on which the casket or coffin is carried if it is not placed on the bier in the first instance. And, one feature of this construction is that the bier 25 may be reduced in length by rearrangement of the members making the same, so that the same parts may be used for a bier when a full size coffin or casket is to be placed thereon, or may also be as readily 30 used when a smaller size of coffin or casket is carried.

My invention consists of constructions whereby the above stated ends are effectively attained, as well as many others not 35 stated in detail at this time but which will appear as understanding of the invention is had from the following description, taken in connection with the accompanying drawings, in which,

40 Fig. 1 is a perspective view of the bier in assembled form and with a casket carried thereon.

Fig. 2 is a perspective view of the assembled bier, looking at the same from the 45 rear.

Fig. 3 is a perspective view of the bier assembled in a different form and closed at all sides, being shorter for shorter length caskets.

50 Fig. 4 is a perspective view showing the elements used in the construction of the bier separated from each other.

Fig. 5 is a rear elevation of the upper 55 end of the center post used, the figure being enlarged, and

Fig. 6 is a fragmentary elevation of one

of the plates used and showing the key-hole slot therein which receives a headed screw on the uprights or posts used in connecting the parts together.

Like reference characters refer to like parts in the different figures of the drawings.

In the construction of the bier, two front plates 1 and 2 of flat metal are used, and in 65 the formation of the same, any desired moulding effects and ornamentation may be made thereon, this not being shown as it is not any mechanical feature of the invention. Two end plates 3 are also used. 70 Each of the plates 1, 2 and 3 has a key-hole slot 4 cut therethrough adjacent each corner, the larger substantially circular portion 4^a of the slot being located below the narrower vertical portion 4^b thereof. 75

A number of corner posts 5 are used in the construction, the same being adapted to be located vertically and each having two sides located at right angles to each other. Each post at its lower end is equipped with 80 a caster 6. Each post at both its upper and lower ends and on the inner side of each of the two parts of the post located at right angles to each other is equipped with a headed screw 7 inserted into the post so as 85 to leave a portion of the shank of the screw out of the post, thereby spacing the head a short distance from the inner side of the post. In addition, a center post 8 is used, 90 the same, at its upper and lower ends and on its rear side carrying two of the screws 8 inserted into the post in the same manner described with reference to the screws inserted into the corner posts 5.

In the assembly of the parts, the front 95 plates are connected to the center post 8 by placing the same at their inner ends against the back of the posts, the heads of the screws 7 on said post being passed through the larger parts 4^a of the slots 4, the plates being then moved downwardly so that the shanks of the screws pass into the narrower vertical portions 4^b of said slots. The outer ends of the plates are attached in like manner to the front corner posts 5, being connected to one of the right angular parts thereof. The ends 3 are connected to the other parts of said front corner posts in the same manner, and at the rear ends of the ends 3, rear corner posts are connected 100 in like manner. This makes a bier on which a full length casket 9 may be placed for 105 110

support, as shown in Fig. 1, or the casket may be carried on a truck and the bier used as a cover or screen to the truck whereby it will not show from in front.

5 The same parts may be assembled as shown in Fig. 3, with the post 8 eliminated, the parts 1 and 2 constituting the front and back of the bier and the ends 3 the ends thereof, being connected to the corner posts 10 5, as shown. This makes a more permanent construction and on it shorter caskets, such as used for children, may be carried. And for show rooms, the four-sided bier construction is preferred. It is apparent that 15 a four-sided bier may be constructed for the longer lengths, the construction shown in Fig. 2 being added to by two additional plates and an additional post 8 at the back open side, connected together and to the rear 20 corner posts the same way that the front plates 1 and 2 and the center post are connected together and to the front corner posts. For more or less permanent use, the 25 screws 7 may be tightened after assembly of the parts to render the disconnection of the parts not likely to occur.

This construction described is simple, economical to produce, and especially strong and satisfactory. The invention is defined 30 in the appended claims and all forms of structure coming within their scope are to be considered as comprehended by the invention.

I claim:

35 1. In a construction of the class described,

a front plate adapted to be vertically positioned, said plate at each end being formed with a plurality of key-hole slots, the larger portions of the slots being located below the narrower portions thereof, corner posts one 40 at each end of the front plate, the end edges of the plate being located back of the corner posts, headed members attached to the posts at the rear sides thereof, one for each slot in the front plate, the plate and posts being detachably connected together by passage of the said members through the slots, and two end plates, one at each end of the front plate connected to the corner posts and extending to the rear therefrom. 45 50

2. In a construction of the class described, a front plate adapted to be vertically positioned and divided vertically between its ends to make two parts, each of said parts of the plate at each end being formed with a plurality of key-hole slots, a corner post at each end of the plate and an intermediate post located at the vertical division of the front plate, said corner posts and intermediate post having headed screws inserted 55 into the same at their rear sides for entrance into the slots in the front plate parts to detachably connect the parts of the plates and the posts together, and two end plates, one at each end of the front plate detachably connected to the corner posts and extending to the rear therefrom. 60 65

In testimony whereof I affix my signature.

JAY H. METCALF.
